Primary Examiner — Catherine Tuttle*(74) Attorney, Agent, or Firm* — Linda M. Sivik(57) **CLAIM**

The ornamental design for a combined container and pump, as shown and described.

DESCRIPTION

FIG. 1 is a perspective view of the combined container and pump embodying our new design;

FIG. 2 is a left side elevational view thereof;

FIG. 3 is a right side elevational view thereof;

FIG. 4 is a rear elevational view thereof;

FIG. 5 is a front elevational view thereof;

FIG. 6 is a plan view thereof; and,

FIG. 7 is a bottom plan view thereof.

The broken lines shown in FIG. 7 are for illustrative purposes only and form no part of the claimed design.

1 Claim, 5 Drawing Sheets(56)
